COMPOSITIONS FOR TINTING HAIR

Frederick M. Lipman, Yonkers, N. Y., assignor
to Charles Marchand Company, New York,
N. Y., a corporation of Delaware

No Drawing. Application January 26, 1951,
Serial No. 208,052

4 Claims. (Cl. 167—88)

1

This invention relates to a method and compositions for tinting hair and more particularly to stable, nonhygroscopic hair tinting concentrates containing benzene phosphonic acid.

The use of coal tar dyes such as those acid dyes listed as suitable for foods, drugs, or cosmetics by the United States Food and Drug Administration in hair tinting concentrates has been practiced in the past. However, the compositions of the prior art have had a serious drawback in that the concentrates, even when packed in so-called moisture-proof containers, tend to pick up moisture from the atmosphere, with consequent deterioration of the dyes themselves and, in some cases, of the containers in which they are packed. The stained containers present an unattractive appearance, rendering the packaged concentrates commercially unsalable, and they must be returned to the manufacturer. The returned dyes cannot be effectively recovered and, as a result, a serious economic loss is sustained. Even more important than the actual return of unsalable merchandise is the loss of good will on the part of the purchaser who receives a package of deteriorated dye, the deterioration of which has been concealed by the package. This customer is lost, and cannot be regained.

It is an object of this invention to produce hair tinting concentrates which are nonhygroscopic and which may be stored over long periods of time without deterioration of the dyestuff or of the containers in which the concentrate is packed.

I have discovered that if benzene phosphonic acid ($C_6H_5PO(OH)_2$) is used as the acid dye-fixing agent in a hair dyeing concentrate, the concentrate will not absorb water from the air and will remain effective in storage over long periods of time without any staining or deterioration of the package in which the concentrate is put up for sale. Furthermore, such concentrates, when dissolved in the proper amount of water, form aqueous solutions of excellent dyeing powers, which are in no way injurious to the hair or skin to which they are applied.

Normally, hair tinting concentrates are available as crystalline or powdered concentrates to be dissolved in a stated quantity of water before application. Such a concentrate may be prepared, according to the present invention, by mixing from two to fifty parts of a suitable non-toxic coal tar dye of the so-called acid type or mixtures of such dyes with from 50 to 2,000 parts of benzene phosphonic acid.

2

For use in tinting hair, the concentrate should be dissolved in water in such quantities that one quart of the solution contains from about 0.002 to 0.05 gram of dye, and from about 0.05 to 2.0 grams of benzene phosphonic acid. If the solution contains less than 0.05 gram of acid, the dyeing rate becomes extremely slow, since the acidity of the solution is not sufficient to fix the dye upon the hair, and if more than about 2.0 grams of the acid is present, the acidity of the solution is so high that there may be danger of skin or eye irritation or even permanent damage. The solution may then be applied to the hair in any convenient manner, to effect tinting thereof.

The benzene phosphonic acid may be used with acid dyes alone, or in combination with a buffer or diluent such as monobasic ammonium phosphate, or sugar, or boric acid. Because it is substantially unaffected by moisture either alone or in combination with benzene phosphonic acid, boric acid is preferred. It is necessary, however, that benzene phosphonic acid be present in the mixture within the proportions specified above, since boric acid alone, in combination with the dyes, will not produce a solution of sufficient acidity to fix the dye.

In order that those skilled in the art may more fully appreciate my invention and the method of carrying it out, the following examples of concentrates prepared according to my invention are given, it being understood that the quantities are those which, when mixed with one quart of water, produce an efficient and practicable tinting composition for home use:

EXAMPLE I

Henna hair rinse

	Grams
D & C Brown #1	0.011
Ext. D & C Red #13	0.003
Benzene phosphonic acid	0.500
Boric acid	1.500

EXAMPLE II

Auburn hair rinse

	Grams
Ext. D & C Red #13	0.0063
D & C Black #1	0.0021
F D & C Yellow #1	0.0147
D & C Red #33	0.0042
Benzene phosphonic acid	0.1000
Boric acid	1.9000

3

EXAMPLE III

Platinum hair rinse

	Grams
F D & C Blue #1	0.00023
D & C Red #33	0.00046
D & C Black #1	0.00023
Ext. D & C Violet #2	0.00130
Benzene phosphonic acid	1.00000

It will be understood, of course, that my invention is not limited to the exact proportions specified in the examples, nor is it limited to the use of the dyes of the examples. Any nontoxic acid dye, or combinations of such dyes, may be used to produce hair rinses of any desired color or tinting power. The concentrates produced according to this invention will remain stable over long periods of time, and will not pick up moisture from the air, thus obviating the necessity of providing expensive moisture-proof packaging, and eliminating the economic loss sustained by reason of the unsalability of deteriorated or stained packages, and loss of good will due to the dissatisfaction of purchasers receiving deteriorated concentrates in place of the top quality concentrates which they believe they are buying.

Having now described my invention, what I claim as new and useful is:

1. As a new composition of matter, a dry hair tinting concentrate comprising nontoxic acid dye material and benzene phosphonic acid, in the proportions of from about 2 to about 50 parts by weight of dye to from about 50 to about 2000 parts by weight of benzene phosphonic acid.

2. As a new composition of matter, a dry hair tinting concentrate consisting essentially of the following ingredients in approximately the proportions set forth, all parts being by weight:

	Parts
D & C Brown #1	11
Ext. D & C Red #13	3
Benzene phosphonic acid	500
Boric acid	1500

4

3. As a new composition of matter, a dry hair tinting concentrate consisting essentially of the following ingredients in approximately the proportions set forth, all parts being by weight:

	Parts
Ext. D & C Red #13	63
D & C Black #1	21
F D & C Yellow #1	147
D & C Red #33	42
Benzene phosphonic acid	1000
Boric acid	19000

4. As a new composition of matter, a dry hair tinting concentrate consisting essentially of the following ingredients in approximately the proportions set forth, all parts being by weight:

	Parts
F D & C Blue #1	23
D & C Red #33	46
D & C Black #1	23
Ext. D & C Violet #2	130
Benzene phosphonic acid	100,000
